UNITED STATES PATENT OFFICE.

HENRY S. DODD, OF TORONTO, ONTARIO, CANADA, ASSIGNOR, BY DIRECT AND MESNE ASSIGNMENTS, OF ONE-FOURTH TO JAMES R. L. STARR AND THREE-FOURTHS TO SAFETY ELECTRIC APPLIANCES, LIMITED, BOTH OF TORONTO, ONTARIO, CANADA.

ELECTRIC SWITCH.

Application filed September 20, 1921. Serial No. 502,063.

To all whom it may concern:

Be it known that I, HENRY S. DODD, a subject of the King of Great Britain, and resident of the city of Toronto, county of York, Province of Ontario, in the Dominion of Canada, have invented certain new and useful Improvements in Electric Switches, described in the following specification and illustrated in the accompanying drawings, that form part of the same.

The principal objects of this invention are, to eliminate arcing in electric switches to overcome the difficulties and damages consequent thereto, and to devise a form of switch which will operate the moving contact to clear the stationary contact with a very rapid action.

The principal feature of the invention consists in the novel construction and arrangement of parts, whereby a pivotal switch arm is swung on its pivot and held securely in either the open or closed position by a toggle connection operating against the pressure of a compression spring.

A further important feature consists in the novel construction and arrangement of a rotatable contact adapted to continuously alter its contacting surface in operation.

In the drawings, Figure 1 is a side elevational view of my improved switch.

Figure 2 is a vertical sectional view showing the relative position of the parts when the switch is in the position illustrated in Figure 1.

Figure 3 is a vertical sectional view showing the position of the parts when the switch is open.

Figure 4 is a front elevational view of the switch member.

In the construction of switch herein illustrated, a back plate 1, preferably formed of sheet metal, is secured to a base block 2 of insulating material being provided with side flanges 3 to form a rigid structure and from the upper ends of the side flanges extend a pair of parallel arms 4.

A pivot pin 5 extends across the space between the arms 4 at the upper ends. Upon the pivot pin and to the outside of the arms 4 is pivotally suspended a forked member 6 which is formed of a suitable insulating material such as bakelite, such

forked member having a central downward extension 7.

A circular hole 8 extends transversely through the central extension 7.

A pin 9 of smaller diameter than the hole 8 is arranged to extend through and beyond the sides of the extension 7 and upon the ends of this pin are mounted the enlarged cylindrical members 10 which form the contacting surfaces of one member of the switch.

A hole 11 extends downwardly through the central portion 12 of the fork member 6 and connects with the transverse hole 8 and in the hole 11 is slidably arranged a pin 13 of insulating material which is adapted to engage the transverse pin 9. The pin 13 is formed with a jaw-shaped upper end 14 in which is pivotally supported a bifurcated bar 15.

A coil compression spring 16 encircles the bifurcated bar 15, the lower end resting upon the pivot pin 17 connecting the pin 13 and member 15.

A washer 18 slidably encircles the bar 15 at the upper end of the spring.

A pair of arms 19 are pivotally mounted upon the pivot pin 5 at the inward side of the arms 4 and are connected at the lower ends by a cross pin 20 which extends into the slot 21 in the bifurcated end of the bar 15 and bears against the washer 18.

The upper ends of the arms 19 are here shown pivotally connected to a tubular bar 22 which forms the switch operating member when used for certain purposes, such as in electric irons but the arms 19 may be operated in any suitable manner to be swung on their pivots.

The swinging of the arms 19 on their pivots causes the pin 20 to slide in the slot 21 and press against the washer 18, thereby compressing the spring 16. The sliding action allows the bar 15 to swing on its pivot in the jaw end of the pin 13 and as the axis of the pin 20 crosses the line between the axis of the pivot of the arms 19 and the axis of the pivot pin 17, the pressure of the spring will cause the forked member 6 to swing on its pivot and such action will be very rapid.

The base block 2 is formed to support a pair of plates 23 insulated from each other and arranged to extend to either side of the

central portion 12 of the forked member 6 so as to be engaged by the cylindrical ends 10 of the switch pin 9.

The upper ends of the plates 23 are each formed with a notch 24 into which the cylindrical ends 10 enter and contact at two points. The lower side of the notches is arranged to slope upwardly and outwardly so that the rollers will engage the surface 10 thereof and ride up thereon.

The pressure of the spring 16 against the pin 13 compresses the transverse pin 19 to the lower side of the hole 8, consequently the transverse pin when the cylindrical 15 ends 10 come in contact with the plates 24, may lift within the hole 8 and a spring pressure contact is always assured.

The action of this switch is extremely positive being of the toggle form and by 20 the simple operation of the arms 19 being swung upon their pivots, the switch arm may be operated to engage or disengage the plates 23 and the disengaging as well as the engaging action is a snappy movement 25 which will effectively prevent the drawing of an arc. The arrangement of the contact pin 9 loosely within the hole 8 not only allows of a spring contact and a consequent self-adjustment so that wear will not affect 30 the switch but it also enables the pin turning freely and each time it is brought into contact with the plates 23 the frictional engagement will create a rolling effect and a new surface will be brought to bear on 35 same. This will ensure very positive contacts at all times.

The parts are extremely simple and of a strong and durable nature and will not be liable to get out of order.

40 The contact plates 23 are each provided with suitable binding screws 25 to which the electrical connections are secured.

This form of switch has been designed particularly for use in small electrical apparatus such as irons but it is capable of 45 application for many different purposes.

What I claim as my invention is:

1. In an electric switch, a pair of rigid contacts having inclined surfaces, an insulating member pivotally supported to swing between said contacts, a conductor member

loosely supported transversely of said pivotal member and adapted to ride on to said contacts, spring means for holding said conductor to its outward position, and means 55 for swinging said insulator member on its pivot.

2. In an electric switch, a pivotal switch arm, a rolling contact member loosely mounted on said switch arm, a fixed contact presenting a surface arranged in an inclined relation in respect to the movement of the switch arm, resilient means for holding said roller contact outwardly toward the inclined surface of said fixed contact, and 60 means for swinging the switch arm on its pivot.

3. An electric switch, comprising, a pivotal switch arm having a transverse orifice in the free end, a metallic contact member 70 loosely arranged in said orifice, a fixed metallic contact adapted to be engaged by said loose contact, a slidable member carried in said switch arm and engaging said loose contact, a slotted bar pivotally connected to 75 the outer end of said slidable member, a compression spring encircling said slotted bar and engaging said slidable member, and an arm supported on a fixed pivot having a pin extending into said slotted bar and engaging said spring.

4. In an electric switch, the combination with an insulating base, of a rigid member secured to said base having a pair of upwardly extending arms, a bifurcated member 85 of insulating material pivotally suspended from said arms and having a transverse orifice in the free end, a roller member loosely mounted in said orifice and projecting from the sides of said bifurcated member, a pair of contact plates rigidly supported from the base having angular notches adapted to be engaged by said roller member, a member slidably arranged in said bifurcated switch arm and engaging said 90 loose roller member, a bar pivotally connected with said slidable member, a compression spring encircling said bar, and a member mounted on a fixed pivot and having slidable contact with said pivotal bar.

HENRY S. DODD.
